UNITED STATES PATENT OFFICE

HILMER F. RODLER, OF WEST NEW YORK, NEW JERSEY, ASSIGNOR TO CALVIN J. MUMMERT, OF WEST NEW YORK, NEW JERSEY

IGNITION DEVICE FOR OIL BURNERS

Application filed November 26, 1926. Serial No. 150,722.

My present invention relates to means for insuring the ignition of the heating fuel in an oil burner mechanism and, among the objects thereof, are to provide a construction such that the disintegrated fuel will be exposed to heat over a larger area than has heretofore been customary in this art; to provide a device of the class indicated in which a plurality of igniting flames will act through a considerable area to cause an ignition of the fuel which it is desired to ignite; to provide an improved device for the purpose indicated; to provide an improved method of igniting fluid fuel; and such further objects, advantages and capabilities as will hereafter appear and as are inherent in the construction disclosed herein.

My invention further resides in the combination, construction and arrangement of parts illustrated in the accompanying drawing and, while I have shown therein what is now considered the preferred embodiment of my invention, I desire the same to be understood as illustrative only and not as limiting said invention.

In the drawing annexed hereto and forming a part hereof, Fig. 1 shows a plan view of the ignition means and air control collar which is to be installed within a furnace or similar structure in which a fire is to be maintained; Fig. 2 is a transverse section of the structure shown in Fig. 1, substantially along the plane indicated by the line 2—2, Fig. 1; Fig. 3 is a fragmentary transverse section of the construction shown in Fig. 1, taken substantially along the plane indicated by the line 3—3; Fig. 4 is a fragmentary transverse section taken substantially along the plane indicated by the line 4—4, Fig. 1; Fig. 5 is a fragmentary sectional elevation showing my improved construction in its relation to the burner mechanism and air control collar and valve.

Referring more in detail to the annexed drawing, numeral 1 denotes the horizontal base portion of the venturi and numeral 2 denotes the air ring or collar rising from this base plate and serving to direct the air upwardly against the under side of the rotating head 3 by means of which the oil is nebulized

and thrown outwardly toward the walls of the furnace. Air vanes 4 are secured to the under side of the head 3 and extend downwardly along the shaft 5 by means of which the head 3 is carried and rotated. An air regulating collar or plate 6 is located adjacent the opening through the throat 2 and regulates the amount of air permitted to reach the vanes 4.

Formed integrally with the base plate 1 are walls 7 and 8 which form a channel 9 for the passage of the igniting gas. This latter is admitted through an opening 10 in the plate 1 and moves to both right and left, passing through the extensions 11 and 12 of the channel 9 and out through openings 13 and 14 into the open spaces 15 and 16 where it is ignited. It is not considered necessary in this instance to disclose the means whereby the gas is ignited, it being sufficient to state that such means is provided for this purpose.

An air deflection ring is formed, partly integrally with the air collar 2 and wall 7, as shown at 17, and is partly separated therefrom, as shown at 18. This latter, at its inner circumference, fits against a shoulder 19 and rests upon a ledge 20. Its ends rest upon the outwardly extending ledges 20^a and fit against the shoulders 21. The upper surface of this partial ring 18 has the same contour as the upper surface of the part thereof which is integral with the collar 2 and walls 7, thus forming a substantially continuous and uninterrupted upper surface, when the device is assembled, this upper surface being shown in Fig. 1 where part 18 appears and directly opposite the same between the shoulders 21, the latter being designated by the numeral 22. The upper end of the throat or collar 2 is denoted by numeral 23 and it is the outer face of this which forms the abutment 19.

It will be obvious from the foregoing that the rotation of the head 3 and vanes 4 will drive air outwardly tangentially, this air passing upwardly through the collar 2 and being regulated in amount by the position of the valve member 6 with relation to the throat or air collar. This air which is thrown off tangentially by the vanes 4 passes over the upper surface of the ring 18 and strikes

the upwardly curved flange 24, which forms a part of the ring 18 and is thus directed upwardly and outwardly transversely of the fuel thrown off from the upper surface of the head 3. It is thus thoroughly co-mingled with this fuel and is in proper condition to be ignited. Preferably slightly before the beginning of the flow of oil the gas entering through opening 10 and passing through channels 9, 11, 12, 13 and 14 is ignited in the compartments 15 and 16 and burns therein. The mixture of air and oil which is heated over the opening 16 helps to raise the temperature of the mixture over opening 15 and ignition will therefore taken place here and work backwardly to the opening 16. This gives a sheet of flame between these two openings and this flame, which results from the burning of the mixture of air and oil, is intensely hot, as compared with the gas flame. This hot flame therefore ignites the mixture of air and oil around the remainder of the circle. This flame between the openings 15 and 16, which may be termed gas nozzles, might be called a flaming arc, on account of its length, which is approximately 75 degrees. It will be readily understood that a flame of this size will be more effective in producing ignition of the mixture of the gas and oil than would a single flame produced by one of the gas nozzles alone. It has been found in use that this device is extremely efficient in causing ignition of the fuel in an oil burning heater.

It is of course understood that the specific description of structure and method set forth above may be departed from without departing from the spirit of my invention as set forth in this specification and the appended claims.

It is intended to claim both broadly and specifically the various novel subjects matter disclosed herein and I therefore desire that failure to insert any claim commensurate with the scope of my invention be not construed as an abandonment thereof.

Having now described my invention, I claim:

1. An ignition unit for oil burners comprising a base plate and air collar, said air collar having a groove at its upper end extending part way around the same, walls integral with the collar forming a gas channel, a gas admission part opening into said channel, a pair of gas burners connected with said channel at separated points around the periphery of the collar, and a ring around the air collar and resting in the groove and supported by the collar.

2. An ignition unit for oil burners comprising a base plate and air collar, walls integral therewith forming a gas channel, a portion of one of the walls forming a part of an air deflection ring, a portion of a separate ring cooperating with said surface to

complete the air deflection ring, a gas admission port opening into said channel, and a pair of gas burners connected with said channel at separate points around the periphery of the collar.

3. A fuel ignitor of the character indicated including an air admission collar to direct air into an oil burner chamber, a projection from one side of the collar having a gas carrying channel therein and a port for admitting gas to said channel, and a pair of burners connected with said projection and having communication with the channel whereby gas is simultaneously admitted to or shut off from both burners, said burners including cups in which combustion may take place.

In witness whereof, I hereunto subscribe my name to this specification.

HILMER F. RODLER.
